GRINDING MACHINE CONSTRUCTION

Filed Sept. 13, 1928 2 Sheets-Sheet 2

UNITED STATES PATENT OFFICE

JACOB DE KONING, OF GRAND RAPIDS, MICHIGAN, ASSIGNOR TO GALLMEYER & LIVINGSTON COMPANY, OF GRAND RAPIDS, MICHIGAN, A CORPORATION OF MICHIGAN

GRINDING MACHINE CONSTRUCTION

Application filed September 13, 1928. Serial No. 305,628.

This invention relates to a mechanism for accurately positioning the work head of a grinding machine.

The main object of this invention is to provide an improved form of simple and efficient mechanism which will impart both a slow and a fast motion to a grinder head for raising and lowering it on its supporting frame.

An illustrative embodiment of this invention is shown in the accompanying drawings, in which:

Fig. 1 is a perspective view of a grinding machine equipped with my improved mechanism.

Fig. 2 is a fragmentary vertical sectional view taken on the line 2—2 of Fig. 3.

Fig. 3 is a fragmentary horizontal sectional view taken on the line 3—3 of Fig. 2.

Fig. 4 is an enlarged fragmentary sectional view taken on the line 4—4 of Fig. 3.

Fig. 5 is an enlarged fragmentary detail view in face elevation of the operating hand wheels.

In the construction shown in the drawings, a grinding machine having the usual vertically disposed supporting frame 1 and horizontally disposed work table 2 is shown provided with a grinding head supporting frame 3 vertically slidable on the frame 1 in guideways formed by the frame 1 and cleats 4 and 5 secured thereto by screws or the like 6. The frame 3 carries a horizontally disposed shaft 7 journalled thereon, one end 35 of which carries a grinding wheel 8 and the other end of which has a belt pulley wheel 9 keyed thereto.

My improved mechanism for raising and lowering the grinding head supporting frame 40 comprises a vertically disposed threaded shaft 10 swivelly mounted at its lower end 11 to the frame 3 and threadably engaged in an upstanding boss 12 formed at the top of the supporting frame 1. The lower end 45 of the threaded shaft 10, close to its point of swivel connection to the frame 3, has a worm gear 13 rigidly mounted thereon which meshes with a driving worm 14 carried on the inner end of a shaft 15 which is journalled in a sleeve 16. The outer end of the shaft

15 carries a hand wheel or knob 17 keyed thereto, the base of which has a ring-shaped gauge 18 held under the overlapping heads of a screw 19 and knurled thumb screw 20. The gauge 18 is so mounted that loosening of the thumb screw 20 will permit the gauge to be rotated relatively to its supporting base which is integral with the hand wheel 17.

The outer end of the sleeve 16 has a hand wheel 21 keyed thereto for manual rotation thereof and the inner end of said sleeve is provided with a spur gear 22 which meshes with a pinion 23 secured to one end of a countershaft 24. The countershaft 24 is journalled in a bearing 25 which is integral with a portion of the housing 3 and the end of the countershaft opposite the gear 23 has a spur gear 26 secured thereto which meshes with a pinion 27 integrally formed on the outer end of the driving worm 14. The ratios between the gears 22, 23, 26 and 27 is such that a single revolution of the gear 22 will impart several rotations to the driving worm 14.

Means are provided for indicating the relative positionings and adjustments of the hand wheels 17 and 21 and comprise a pointer hand 28 secured by screws 29 to one of the spokes of the hand wheel 21, the end of the pointer hand 28 extending radially inward and slightly overlapping the scale 18. A pointer 30 integrally formed on a collar 31 is provided for the hand wheel 21, the tip end thereof extending partially around the outer rim of the hand wheel and being in slightly spaced relation thereto as shown most clearly in Fig. 3. The collar 31 is rotatably mounted on a portion of the housing 3 and may be secured in any desired position by a set screw 32 which has a knurled head adapted to be grasped by the fingers of the operator.

In the operation of this device, when it is desired to impart a very small movement to the grinder head to either raise or lower the head with respect to the work table 2, the knob or small hand wheel 17 is grasped by the operator and rotated in the appropriate direction. Rotation of the wheel 17 rotates the driving worm 14 which meshes with the

100

worm gear 13 rigid on the threaded shaft 10. Rotation of the shaft 10 raises or lowers the grinder head housing 3 with respect to the supporting housing 1 by reason of the threaded connection of the shaft 10 through 5 the boss 12.

When a desired position is reached, the ring scale 18 is suitably set and positioned with respect to the pointer 28 so that any slight variation from this position may be 10 read off directly on the scale. A fine adjustment is thus secured to the grinder head.

When rapid motion or coarse adjustment of the grinder head is desired, the large hand wheel is rotated, each revolution thereof imparting a multiplied number of revolutions to the driving worm 14 by reason of the gear train, comprising the gears 22, 23, 26 and 27. The indicator hand 30 may be suitably positioned with respect to the hand wheel 21 by 15 rotating the collar 31 on its supporting housing and securing it in desired position by the set screw 32.

Although but one specific embodiment of 20 this invention has been herein shown and described, it will be understood that numerous details of the construction shown may be altered or omitted without departing from the spirit of this invention as defined by the 25 following claims.

I claim:

1. In mechanism of the character described, a pair of slidably connected elements, a screw swivelled on one of said elements and threaded to the other of said elements, a gear rigid on said screw, a driving worm meshing with 30 said gear for rotating said screw, a shaft directly connected to said driving worm, a hand wheel on said shaft for rotating the 35 same, a sleeve surrounding said shaft and rotatable with respect thereto, a hand wheel on said sleeve for manually operating the same and a train of gears connecting said sleeve and said shaft for rotating said shaft at an increased speed with respect to said sleeve 40 hand wheel.

2. In mechanism of the character described, a pair of slidably connected elements, a screw swivelled on one of said elements and threaded to the other of said elements, a gear rigid on said screw, a driving worm meshing with said gear for rotating said screw, a shaft directly connected to said driving worm, a hand wheel on said shaft for 50 rotating the same, a sleeve surrounding said shaft and rotatable with respect thereto, a hand wheel on said sleeve for manually operating the same, a gear on said shaft, a gear on the inner end of said sleeve, a counter-shaft journalled with its axis parallel to the axis of said shaft and sleeve, and gears on 55 said counter-shaft meshing with said shaft and sleeve gears for rotating said shaft at a different speed with respect to said sleeve 60 hand wheel.

3. In mechanism of the character described, a pair of slidably connected elements, a screw swivelled on one of said elements and threaded to the other of said elements, a worm gear rigid on said screw, a driving worm meshing with said worm gear for rotating said screw, a shaft directly connected to one end of said driving worm, a spur gear on the other end of said driving worm, a hand wheel on said shaft for rotating the same, a sleeve surrounding said shaft and rotatable with respect thereto, a hand wheel on one end of said sleeve for manually operating the same, a spur gear on the other end of said sleeve, a countershaft journalled adjacent said driving worm with its axis in spaced parallel relation thereto, a spur gear on one end of said countershaft meshing with said sleeve gear, and a spur gear on the other end of said countershaft meshing with the worm shaft's spur gear whereby rotation of said sleeve hand wheel will impart rotation to said driving worm.

4. In mechanism of the character described: a rotatable driven element having a worm gear; a pair of driving shafts, relatively rotatable one within the other, one of them having a worm meshing with the worm gear and having also a spur gear, the other shaft having a spur gear; a counter shaft having gears meshing with said spur gears respectively.

In testimony whereof I have hereunto set my hand at Grand Rapids, Michigan this 10th day of September, 1928.

JACOB DE KONING.
